UNITED STATES PATENT OFFICE.

MERLE J. WIGHTMAN, OF SEATTLE, WASHINGTON, ASSIGNOR TO RAILWAYS' ACCESSORIES COMPANY, OF SEATTLE, WASHINGTON, A CORPORATION.

RAIL-SUPPORTING DEVICE.

1,183,261

Specification of Letters Patent. Patented May 16, 1916.

Application filed January 12, 1914. Serial No. 811,751.

To all whom it may concern:

Be it known that I, MERLE J. WIGHTMAN, citizen of the United States, residing at Seattle, in the county of King and State of Washington, have invented a certain new and useful Improvement in Rail-Supporting Devices, of which the following is a specification:

My invention relates to improvements in devices for supporting and uniting the intersecting portions of the rails of railroads at points where such railroads cross each other and where they diverge one from another, and the object of my invention is to provide devices by which the end portions of rails of a railroad or the intersecting portions of the rails of two railroads may be permanently and securely supported to sustain abnormally great strains to which they may be subjected, such devices being adapted to be embodied in, or associated with, railroad crossings, frogs, switch points and guard rails. I attain this object by devices illustrated in the accompanying drawings 25 wherein:

Figure 1 illustrates a rail secured to a railroad tie by some of the means embodied in my invention, by a view in cross-section on broken line *e*, *e* of Fig. 2; Fig. 2 shows the same by a view in side elevation with a part of a supporting plate broken away more clearly to disclose other parts; Fig. 3 illustrates the same form of means associated with a reversible double headed rail by a view in vertical cross-section; Fig. 4 illustrates parts of my invention, as employed in securing to a railroad tie two adjacent rails, by a view in cross-section; Fig. 5 illustrates by a view in cross-section another form of parts of my invention as employed in supporting two rails, one of which is disposed at a higher elevation than another to adapt it to serve as a guard-rail; Fig. 6 is a view in cross-section showing parts of my invention adapted to support a railroad rail and a guard-rail whose cross-section is of rectangular shape; Fig. 7 illustrates by a plan view a frog embodying parts of my invention whose cross-section on broken line *x*, *x* is shown in Fig. 14; Fig. 8 is a view in perspective on a reduced scale of a part of the device illustrated in Fig. 7; Fig. 9 is a plan view showing one half portion of a railroad crossing embody-

ing a form of my invention; Fig. 10 is an enlarged view of the same in cross-section, on broken line *y*, *y* of Fig. 9; Fig. 11 is an enlarged plan view showing one half portion of a railroad crossing better adapted for street railways; Fig. 12 is an enlarged view in cross-section on broken line *z*, *z* of Fig. 11; Fig. 13 is an enlarged view in perspective of one of the riser blocks embodied in the device of Fig. 11, and Fig. 14 is a view in cross-section on line *x*, *x* of Fig. 7. 65

Like reference numerals indicate like parts throughout the drawings.

In my co-pending application, Serial No. 802,952, for Letters Patent for rail joints, filed in United States Patent Office, Nov. 25, 70 1913, I have disclosed certain devices that are adapted to be associated with the abutting ends of two railroad rails to form a rail-joint that shall securely unite such abutting ends and maintain them in permanent alignment. In my present invention I have associated different forms of those same devices with other elements to produce railroad crossings, frogs, switch-points, and to rigidly unite a railroad rail with a guard-rail. In my invention of said co-pending application are embodied the elements of an arch structure, but in my present invention, in addition to such elements of arch structure, I have embodied the elements and principles that are involved in the construction of a dome. 85

Referring to Figs. 1 and 2 of the drawings, a rail 15, is fixed and supported, like the keystone of an arch, between the clamping members 17, 17, such clamping members 17, 17 being disposed to extend each from said rail 15 to the inner obliquely disposed surface of one of the upwardly projecting side flanges 18, of the base-plate 16, such clamping members 17, 17 serving like the voussoirs of an arch and engaging with the under surfaces of the heads and with the upper surfaces of the flanges, respectively, of said rail 15 to support, in an arch-like manner, said rail 15 with its base disposed higher than the top surface of said base-plate 16, which base-plate 16 rests upon a railroad tie 19 and is secured thereto by bolts 20 which extend from the upper surfaces of said clamping members 17 downwardly through bolt holes therein, thence through holes on said base-plate 16 and

through holes in the tie 19 as indicated in the drawings.

To prevent the rail 15 from moving in its lengthwise direction with respect to the 5 clamping members 17, 17 I have provided a pin 21 which extends through the web of the rail 15 to project each side therefrom into a recess provided in each of said clamping members 17, 17, such pin 21, however, 10 under some conditions may be dispensed with.

Fig. 3 illustrates a device that is substantially similar to the device of Figs. 1 and 2, except that the rail 22 embodied 15 therein is of the type known as a double headed rail, which may be renewed by turning it upside down when one of the heads becomes worn.

The devices of Figs. 1, 2 and 3 may be employed in securing a single rail to a tie, as 20 to the tie 19, as when such single rail extends from a crossing, frog or switch-point.

Fig. 4 illustrates a plan of construction whereby two rails that are disposed substantially parallel to each other may be held 25 permanently in a rigid relationship with each other by the application of the principle involved in the construction of an arch, supporting elements that are similar 30 to the supporting elements of the devices of Figs. 1, 2 and 3 being employed, as for instance, a supporting base 23, the tie 19, clamping members 24 and bolts 20, while between the rails 25, 25 is disposed a block 35 35 which serves, like the keystone of an arch, to coact with the clamping members 24 and the side flanges 27 of the base-plate 23 to rigidly support said rails 25, 25 above the top surface of the base-plate 23 as shown, 40 such block 26 engaging with the under surfaces of the heads and the top surfaces of the flanges of the adjacent sides of the rails 25, 25, in an obvious manner as shown.

Fig. 5 illustrates a rail 28 supported in 45 association with a guard-rail 29, which guard-rail 29 is disposed at a higher elevation than the rail 28, upon which the wheels of a train may travel, whereby such guard-rail 29 may engage with the outer side of 50 the flange of a wheel to prevent the tread of such wheel from leaving the rail 28.

In the structure of Fig. 5 the block 30 and the members 31, 31, slightly differ in form from the block 26 and the clamping 55 members 24, 24 of Fig. 4, but their function or purpose obviously is the same.

In Fig. 6 I have shown a structure wherein is embodied a guard-rail 32, whose cross-section is rectangular in form, supported in 60 association with a rail 33, a clamping member 34, a block 35 and base-plate 36 which rests on a tie 19, such guard-rail 32 acting also as a clamping member, like one of the elements of an arch, while the rail 33 serves 65 as a keystone of such arch whereby the said

rail 33, the block 35 and the guard-rail 32 may be supported above the top surface of the base-plate 36.

Obviously a structure of Fig. 6 involves the same principle as does the structure of 70 Figs. 4 and 5.

In Figs. 7 I have illustrated a frog embodying the intersecting portions of two rails that cross one another obliquely, in the construction of which frog is involved the 75 principle applied in building a dome and in which are combined the elementary structures of the preceding figures to support the component rails of such frog. In such Fig. 7 a base-plate 37 (which is more clearly 80 shown in perspective by a view on a reduced scale in Fig. 8) is provided with four upwardly projecting lugs 38, 39, 40 and 41, the inner surface of each of which is outwardly inclined, and above said base-plate 85 37 are rails 42 and 43 which are disposed in angular positions to cross each other in a well known manner, which rails are supported in their positions above the base-plate 37 by clamping members 44, 45, 46 and 47 of such angular forms as correspond with the angular positions of said rails 42 and 43, the clamping members 44 and 45 extending from the lugs 38 and 41, respectively, to engage with the heads and flanges of rails 90 42 and 43, while the clamping members 46 and 47 extend from lugs 39 and 40, respectively, to engage with the heads and flanges of the opposite sides of said rails 42 and 43 whereby such rails 42 and 43 conjointly 95 constitute the keystone of a dome, while the clamping members 44, 45, 46 and 47 act as voussoirs. In Fig. 14 I have shown in cross-section on broken line x, x of Fig. 7, the arrangement of the parts of the frog 100 whereby said rails 42 and 43 are sustained in their position above the base-plate 37. Thus it is seen that the structure of Fig. 7, in effect, is a dome that embodies an arched 105 relationship of the parts from side to side and from end to end. In this structure every point along either rail occupies a wedging or keystone position in a separate transverse arch, of the type shown in Fig. 1, or in Fig. 4, and by association of each of 110 such arches with all others therein, any pressure exerted at any point upon either of the said rails is simultaneously transferred to and substantially duplicated in the other. Any movement of, or within, the structure 115 is, therefore, as a unit, the weight upon the near or supporting portion of either rail operating, through the structure, to equally depress all other points therein, whereby to maintain a permanent practical alinement 120 of the rail heads. It will thus be obvious that all parts of this structure are self-adjusting and that wear or abrasion at any of the supporting bearings is automatically 125 taken up by self-adjustment, thus holding 130

every element of the structure continuingly free from relative motion.

In Fig. 9 I have shown one half of a right angled railroad crossing which embodies parts having a dome relation like the parts shown in Fig. 7, except that such parts are adapted for rails which cross at right angles to one another. In said Fig. 9 circular base-plates 48, 48 are each provided with upwardly projecting curved lugs 49, 50, 51 and 52 above which are disposed main line track rails 53, 54 and 55 together with guard-rails 56, 57, 58, 59 and 67 and clamping rails 60, 61, 62, 63, 64, 65 and 66 all of which rails are supported in their positions by clamping members 68, 69, 70 and 71 which respectively extend between the lugs 49, 50, 51 and 52 to engage with the heads and flanges of the rails which respectively are nearest to them.

Fig. 10 by an enlarged cross-sectional view on broken line $y-y$ of Fig. 9, shows the arrangement of parts embodied in the dome-like structure wherein a clamping block 72 disposed between the rails 54 and 57 may be regarded as serving as a keystone of said dome, while a narrower clamping block 73 that is disposed between rails 60 and 54, together with the clamping members 70 and 71 and the rails 60, 54 and 57 may be regarded as voussoirs.

Each of the clamping members 68, 69, 70 and 71 are bolted to their respective base-plate 48 by bolts 74.

In Fig. 10 I have indicated a rod 82 that may extend through holes in the webs of rails 60, 54 and 57 and through the clamping blocks 72 and 73 to project its ends into recesses formed in the clamping members 70 and 71, which rod 82 may serve to prevent an endwise movement of any of the rails with respect to the circular base-plate 48.

In Fig. 11 I have shown the two rails 75, 75 of a street railway-track crossing at right angles another rail 76 that may constitute one of the rails of another railway-track, the intersecting portions of which rails are supported by a rectangular frog embodying my invention whose parts are associated in accordance with the principle involved in the construction of a dome, but such rectangular frogs, as shown, are particularly adapted for street railway crossings. In such Fig. 11 the base-plates 77, 77 are each provided with lugs 78 disposed to extend upwardly, one on each corner of each of the base-plates 77, 77, the inner face of each of such lugs 78 being slightly inclined, as shown more clearly in Fig. 12 at such angle that their frictional engagement with the impinging members will hold the said members against recovery and make the entire structure practically integral. The intersecting portions of the rails 75 and 76 are

disposed above the base-plate 77, and secured in such position by angular clamping blocks 79, 79 and 80, 80; the clamping blocks 79, 79 each extending from the inner surfaces of its respective lug 78 to the heads and flanges of the adjacent sides of the intersecting rails 75 and 76 at the point of their juncture, and the clamping blocks 80, 80 each similarly disposed with respect to its respective lug 78 and the rails 75 and 76, except that each of the said clamping blocks 80, 80 is provided with a recess on its upper and inner side to receive a bar, preferably of hardened steel, that may be termed a "riser block" 81 that is disposed to extend from one clamping block 80 to the adjacent clamping block 80 of a frog to fit within such recesses to engage with the under surface of the head of the rail 75, while the bottom surface of each of the clamping blocks 80, 80 engages with the top surface of the flange of said rail 75.

Fig. 13 by a perspective view more clearly shows the form of the riser block 81 which serves by its position to maintain the weight of a wheel by engaging such wheel's flange when said wheel is running over the cut away portion of the heads of said rails 75 and 76 at the point of their intersection, whereby the tread of a wheel may always be maintained at the same elevation as is the top surface of the rail upon which it is traveling.

It will be seen by referring to Fig. 11 that the riser blocks 81 are held from longitudinal displacement by the widening of their outer ends, and obviously such riser blocks 81 readily may be replaced by new ones when worn by the action of wheel flanges.

What I claim is:

1. In a structure of the class described, the combination with a base-plate having upwardly projecting lugs, of two rails disposed to extend over the top surface of said base-plate, a key block disposed between said two rails in a position to engage with the heads and flanges of the adjacent sides of said two rails and a clamping member disposed to engage with the head and flange of the outer side of each rail and to extend therefrom to rest against one of said lugs whereby said key block may act like the keystone of an arch while said rails and said clamping members may act like the voussoirs of said arch to sustain said two rails in a fixed position above the top of said base-plate.

2. In a structure of the class described, the combination with a supporting base-plate which is provided with upwardly projecting lugs, of two railroad rails disposed so that the axis of one of said rails intersects the axis of the other of said rails at a point over the central portion of said base-plate while the bottom surfaces of said rails

are above the top surface of said base-plate, and clamping members each of which is formed to adapt it to engage with and extend from one of said lugs to the adjacent 5 sides of the intersecting portions of said two rails to engage with the heads and flanges thereof whereby the intersecting portions of said two rails may act like the key-stone of a dome while said clamping members 10 may act like the voussoirs of a dome to support said intersecting portions of said two rails in a fixed position above said base-plate.

3. In a structure of the class described, the 15 combination with a supporting base-plate which is provided with a plurality of upwardly projecting lugs, of two railroad rails that are disposed so that the axis of one of said rails intersects the axis of the 20 other of said rails at a point over said base-plate, each of said rails having a wheel-flange gap disposed adjacent to the point of its intersection with the other of said rails, two riser blocks each of which is disposed over said base-plate in engagement with one side of the head of a different one of said rails with the surface of its highest portion opposite the wheel-flange gap of such different one of said rails, and angular 25 clamping blocks, each disposed to engage with a different one of said lugs and to extend therefrom to support said rails and said riser blocks in a dome-like manner in a fixed position above the top surface 30 of said base-plate.

4. In a structure of the class described, the combination with a plurality of rails disposed with their longitudinal axes in different planes, supporting members engaging said 40 rails, a riser block engaging one or more of said rails and one or more of said supporting members and means for resolving any pressure exerted on any one of said rails into equal pressures between said supporting members and all of said rails.

5. In a structure of the class described, the combination with a plurality of rails disposed with their longitudinal axes in different planes, supporting members engaging 50 said rails and means for resolving any pressure exerted on any one of said rails into equal pressures between said supporting members and all of said rails.

6. In a structure of the class described, the combination with a plurality of rails 55 disposed with their longitudinal axes intersecting, a base-plate provided with upturned lugs, filler blocks engaging said rails and means for resolving any pressure exerted on any of said rails into equal pressures between said filler blocks and said rails.

7. In a structure of the class described, the combination with a plurality of rails disposed with their longitudinal axes in different planes and supported in a plurality of 60 arches, and means for equalizing the pressures in all of said arches.

8. In a structure of the class described, the combination with a plurality of rails disposed with their longitudinal axes in different planes, filler blocks engaging said 70 rails, a supporting base-plate, and means associated therewith whereby said filler blocks are caused to be pressed laterally toward said rails under the weight of a passing wheel load.

9. In a structure of the class described, the combination with a plurality of rails disposed with their longitudinal axes in different planes, supporting members engaging said rails, a base-plate and means for directing a mechanically centering inward pressure upon said supporting members.

10. In a structure of the class described, the combination with a plurality of rails 85 disposed with their longitudinal axes in different planes, supporting means and compression means so disposed that a wheel load on any one of said rails shall be resolved into an inward pressure exerted by the said 90 supporting means equally against all rails.

11. In a structure of the class described, the combination with two rails disposed with their longitudinal axes in different planes, clamping members supporting one 95 of said rails in an arch and means for equalizing the pressure of said clamping members against both of said rails.

In witness whereof I hereunto subscribe my name this twenty-sixth day of December 100 A. D., 1913.

MERLE J. WIGHTMAN.
